O. D. ADAMS

LEAF TURNING GUIDE

Filed Dec. 14, 1925

O. D. ADAMS INVENTOR

BY *Merrill M. Blackburn*
ATTORNEY

UNITED STATES PATENT OFFICE.

OMAR D. ADAMS, OF DAVENPORT, IOWA.

LEAF-TURNING GUIDE.

Application filed December 14, 1925. Serial No. 75,943.

My invention relates particularly to means for assisting in locating a particular group of leaves, sheets, cards, or the like, pertaining to a particular subject matter and then 5 turning these, easily, one at a time to locate the particular leaf desired.

Among the objects of this invention are: to provide means adaptable to large or small books, cards in a file, expanding vertical 10 files, and the like, whereby the leaves of such can be arranged into indicated groups with the indications readily accessible, if not wholly visible, from either side thereof in the case of books, and any desired group 15 quickly and easily reached; to provide means whereby leaves may be readily turned or separated individually as well as by groups, from either side; to provide means whereby cards manufactured with notches at 20 given positions in an edge thereof, may be arranged in a filing case to form any desired guide, or guides, such as those here described; and such further objects, advantages and capabilities as will hereafter appear and as are inherent in the construction disclosed.

My invention resides mainly in the combination, construction and arrangement of parts illustrated in the accompanying drawing but, while I have shown therein a preferred embodiment of my invention, I desire the same to be understood as illustrative only and not as limiting said invention.

In the drawing annexed hereto and forming a part hereof, the figure represents a book having my invention applied thereto. While this is shown as being applied to a dictionary, concordance, or the like, it will be of course understood that it may equally 35 as well be applied to a Bible, a reference book, or any other book as desired. Appropriate marks will be placed in the notches 2 in the edges of the leaves 1, upon the exposed faces of the adjacent leaves. In the present 40 drawing, I have shown the use of the letters of the alphabet but it will of course be understood that if this invention be applied to a Bible the names of the books thereof will replace the alphabet as shown in this 45 drawing. It will also be understood that chapter numbers may replace the letters shown, if desired.

These notches are arranged in two major groups aligned transversely of the leaves, said 50 groups being adjacent each other and being divided into lesser groups separated by one

or more leaves belonging to the other major group. As illustrated the alternate letters A, C, E, G, I, etc., will be in one group, while the remaining letters will appear in 55 the other group. This is true especially with reference to cards and the like, which are accessible from but one direction. In the case of books, and the like, each letter occurs in two adjacent notches as illustrated by 60 the letter F—one F being in the notch with, and facing G, while the other F occurs in the notch with, and facing E. Likewise there is a G which is invisible in the drawing, in the notch with, and facing H, and 65 so on. Hence, one may grasp a bunch of leaves in the right hand with the thumb at G and allow all of the leaves at the left to turn and he will have the words whose initial letter is G; and similarly, when the book is 70 75 in the opposite position, one may grasp a bunch of leaves in the left hand with the thumb at G which is invisible in the drawing, and allow all of the leaves at the right to turn, and he will have the same location 80 as before. In other words, any letter appears upon two pages facing each other.

It may be desired to subdivide one of these groups of leaves by turning the leaves individually until the one desired is found. 85 In this case, a finger or thumb may be placed in one of the notches 3 or 4 and the leaf in which this notch occurs may be permitted to turn without the rest of the leaves turning with it. By then sliding the thumb 90 along the edge of the next leaf and into the other notch another leaf may be permitted to turn. For example, supposing that one has turned to the letter F and desires to turn the leaves 1 of this group, one 95 at a time, he will place the thumb of his right hand in the notch 4 and bend the leaves sufficiently so that the first one will turn to the left. Next he will slide his thumb upward on that page upon which 100 it is resting, until it comes into the notch 3 when that leaf will turn. The thumb is then moved lightly down the page into the notch 4 and then up into the notch 3, thus alternating until the desired leaf is found. This 105 permits the turning of one leaf at a time, with certainty and without difficulty and in no instance are two or more leaves permitted to turn at once. However, it will probably be more convenient for the individual using 110 this invention to place a thumb in line with the set 4 of these notches and a finger in

line with the set 3 and then permit leaves to escape alternately from the thumb and finger.

The notches 5 and 6 at the bottom of the book are particularly useful in small books where the little finger or thumb can be used to prevent the leaves from turning and then, when it is desired to have a leaf turn, move the finger or thumb to the next notch where by one leaf is permitted to turn.

This device is particularly useful for Bibles, especially those made of thin india paper, and for all reference books which are much used, and likewise, for card files. It is especially valuable as an aid to elderly people whose hands are a bit unsteady, in turning the leaves of books with the least effort and annoyance.

In this specification and the appended claims the term "leaf" is intended to cover not only a leaf of a book but also cards, sheets of paper and other materials, and the like.

Having now described my invention, I claim:

1. In a leaf-turning guide, a plurality of leaves or the like having notches in the edges thereof, said notches being of substantially the same size and arranged in two major groups out of alignment with each other transversely of the leaves, the notches of each major group being in alignment trans-

versely of the leaves, and being divided into minor groups separated by a plurality of leaves belonging to the other major group.

35

2. In a sheet turning guide, a group of sheets each having a notch in an edge thereof, said notches all being in alignment transversely of the sheets, another group of sheets, adjacent the first mentioned group, each having in an edge thereof aligned notches, the groups of aligned notches being out of alignment with each other, whereby by the sheets may be separated into general groups, the sheets having other notches in offset relation to assist in fingering the individual sheets.

40

3. In a sheet-turning guide, a plurality of sheets or the like having notches in the edges thereof, said notches being of substantially the same size and arranged in two major groups out of alignment with each other transversely of the sheets, the notches of each major group being in alignment transversely of the sheets and being divided into minor groups separated by a plurality of sheets belonging to the other major group, and indexing information upon two pages facing each other, the information being located opposite a notch in the adjacent sheet.

45

In witness whereof, I hereunto subscribe my name to this specification.

O. D. ADAMS.
